US0D1102626S

(12) **United States Design Patent** (10) **Patent No.:** **US D1,102,626 S**
(45) **Date of Patent:** **** Nov. 18, 2025**

(54) **BRACKET**

(71) Applicant: **Genhua Zeng**, Ganzhou (CN)

(72) Inventor: **Genhua Zeng**, Ganzhou (CN)

(**) Term: **15 Years**

(21) Appl. No.: **29/982,737**

(22) Filed: **Jan. 7, 2025**

(51) LOC (15) Cl. **08-05**

(52) U.S. Cl.

USPC **D8/381**

(58) **Field of Classification Search**

USPC D25/68, 133, 127, 134, 119, 102;
D14/238, 447, 224, 451, 229, 209, 432;
